Prindle, Langdon & Small

UNITED STATES PATENT OFFICE.

LOUIS SCHULTE, OF PITTSBURGH, PENNSYLVANIA, ASSIGNOR TO E. I. DU PONT DE NEMOURS & COMPANY, OF WILMINGTON, DELAWARE, A CORPORATION OF DELAWARE.

BUFFING-MACHINE.

1,329,551.

Specification of Letters Patent.

Patented Feb. 3, 1920.

Application filed July 24, 1918. Serial No. 246,533.

To all whom it may concern:

Be it known that I, LOUIS SCHULTE, of Pittsburgh, in the county of Allegheny and in the State of Pennsylvania, have invented 5 a certain new and useful Improvement in Buffing-Machines, and do hereby declare that the following is a full, clear, and exact description thereof.

My invention has for an object to provide 10 a machine for performing buffing or similar operations in which the work is so supported as to secure uniform pressure of the same against the buffer, and in which vibrations of the machine will be taken up or absorbed 15 without detriment to the same.

Another object of my invention is to provide a machine which can be easily set up on a floor although the floor be uneven, and in which a proper adjustment of the work 20 supporting table may be readily made.

Another object of the invention is to provide a work table driving means which will operate without special adjustments in all positions of the table.

25 Further objects of the invention will be in part obvious and in part specifically pointed out in the description hereinafter contained, in which I have shown one embodiment of my invention, which embodiment however 30 is to be regarded merely as illustrative of its principle.

In the drawings:

Figure 1 is a side view of a machine made according to my invention;

35 Fig. 2 is a plan view of the portion of the machine appearing at the right of Fig. 1;

Fig. 3 is a plan view of the portion of the machine appearing at the left of Fig. 1;

40 Fig. 4 is a section taken on line 4—4 of Fig. 1, looking in the direction of the arrows.

In machines of the type disclosed it has been the practice to provide a large base or frame carrying the different elements of the 45 machine, the work holding table being slidingly carried by such frame upon ways or guides and certain adjustments being provided whereby the distance between the work holding table and the buffing roller could be 50 varied as desired. These machines have been objectionable in that the extensive base required to accommodate the table was often difficult to set up properly upon floors at all uneven, and furthermore, the high speed of 55 the buffing roller tended to set up vibrations

throughout the whole frame work which were very detrimental to the proper action of the machine.

In order to remove the above objectional features, I employ a table support which, in 60 the present instance comprises four independent pedestals 1, 2, 3 and 4 and which can easily be set up wherever desired. Extending respectively between the pedestals 1 and 3 and 2 and 4, are a pair of resilient shafts 65 5 and 6 which form guides upon which the work table 9 may be reciprocated.

A buffing wheel 10 carried by a shaft 11, is positioned over the work holding table 9, by means of a pair of supporting posts 11 70 and 12, having bearings 13 and 14 for receiving the shaft 11. A pulley 15 on the shaft 11 is used to drive the same. The particular type of buffing mechanism used is not essential to my invention, and accordingly will 75 not be described in greater detail.

In order to position the work table properly with respect to the buffing wheel 10, I provide an adjustment for each of the shafts 5 and 6 so that the same may be positioned 80 at any desired height and inclination. In the present embodiment, the upper portion of each of the pedestals 1 to 4 is made hollow and a screw 16 is mounted therein. A collar 17 surrounds each of the screws 16 and each 85 collar is pivotally connected as at 18^a to the adjacent shaft end. Suitable devices are provided to rotate the screws 16 to place the shafts 5 and 6 in any desired position, such as the hand wheels 18 on the pedestals 1 and 90 2 and the worm gears 19 and worms 20 carried by shaft 21, on the pedestals 3 and 4.

In this way it will be seen that the supporting parts for the work table 9 may be set up in any desired location, no matter how uneven may be the elevation of the points upon which the pedestals 1, 2, 3 and 4 are placed, and the hand wheels 18 or shaft 21 turned to adjust the work table 9 to the proper distance from the buffing wheel 10. It is not 100 requisite in any way that the table 9 be maintained horizontal, as has generally been the case, since adjustment may be readily made to permit table 9 to operate in an inclined plane, if desired or necessitated. 105

Since the table 9 is supported upon resilient shafts 5 and 6 any vibration of the parts of the machine are absorbed by such shafts rather than being transmitted to the table 9 so as to interfere with the proper 110

operation of the roller 10 upon the work. Furthermore the spring shafts press the work table uniformly against the surface of the buffing roller 10 so that the roller operates evenly throughout the entire surface of the work.

In order to drive certain parts of the machine I have shown a shaft 22, journaled in brackets 23 and 24 on the pedestals 1 and 2, 10 and carrying a pulley 25. It is desirable to move the roller 10 laterally over the work, and to accomplish this a shaft 26 is driven from the shaft 22 through bevel gears 27 and 28, and such shaft 26 carries at its 15 inner end a crank 27^a. A link 28^a is connected to the crank 27^a at one end, and its other end is secured to a rocker arm 29 which engages a collar 30 on the end of the shaft 11, thus moving the roller 10 laterally 20 during each revolution of the shaft 26.

In prior machines of the types herein-after mentioned, the work table has been driven by devices such as a rack and gear, which require a corresponding adjustment whenever the level of the work table is 25 changed, so that the proper adjustment of the machine was very cumbersome. I have overcome this difficulty by providing a link operating mechanism for the table 9 which 30 needs no special adjustment when table 9 is raised or lowered. In the form illustrated a pair of connecting rods 31 are pivoted to the table 9 at one end, and their other ends are connected to cranks 32 mounted upon a 35 shaft 33 which latter is carried in bearings 34 upon the pedestals 1 and 2. A wheel 35 is also carried by such shaft 33 so that, as this wheel is rotated the table 9 will be reciprocated under the buffing roller 10. If 40 desired wheel 35 may be in the form of a gear which engages a pinion 36 on the driving shaft 22 so as to make the feed of table 9 positive. It is obvious that raising or lowering the table 9 by adjustment of the shafts 45 5 and 6 will in no way interfere with the operating links for the table, since they may readily assume any angular position corresponding to the elevation of the table 9.

While I have described a specific form of 50 the invention, it is obvious that many changes may be made without departing from the principle thereof as defined in the following claims.

I claim:

1. A buffing machine having guides adapted to receive a work holding table, independent supports respectively for the two ends of said guides, and means for adjusting the position of the guides in each of said supports. 55
2. A buffing machine having guides adapted to receive a work holding table, independent supporting pedestals for each end of each of said guides, and means on each of said pedestals for adjusting the position 60 of the corresponding guide. 65
3. A buffing machine having guides adapted to receive a work holding table, independent supporting pedestals for each end of each of said guides, an adjusting screw 70 being provided on each of said pedestals and engaging a portion of the corresponding guide to maintain the same at the desired elevation. 75
4. A buffing machine having a pair of 75 spring shafts adapted to receive a work holding table, independent supporting pedestals for each end of each of said shafts, an adjusting screw being provided on each of said pedestals, each end of said shafts 80 having a collar pivoted thereto and engaging the corresponding screw. 85
5. In a buffing machine, a plurality of independent pedestals, a work holding table, supporting members for said table each extending between a pair of said pedestals, and devices carried by said pedestals for varying the elevation of said members, the devices at the two ends of said members being independently operable. 90
6. A buffing machine having a buffing roller, a work holding table, and a resilient support for said table, whereby the work may be held against the roller with uniform pressure, and vibrations of the machine absorbed. 95
7. A buffing machine having a buffing roller, a work holding table, and a pair of spring shafts receiving said table, and means for moving said table along said shafts, whereby the work may be held against the roller with uniform pressure and vibrations of the machine absorbed. 100

In testimony that I claim the foregoing I have hereunto set my hand.

LOUIS SCHULTE.
